UNITED STATES PATENT OFFICE.

JOHN F. GOLDFING, OF WASHINGTON, DISTRICT OF COLUMBIA.

CONCRETE FLOOR AND CEILING.

1,095,204.

Specification of Letters Patent.

Patented May 5, 1914.

Application filed May 19, 1913. Serial No. 768,534.

To all whom it may concern:

Be it known that I, JOHN F. GOLDFING, a citizen of the United States, residing at Washington, in the District of Columbia, have invented certain new and useful Improvements in Concrete Floors and Ceilings, of which the following is a specification.

The invention relates to concrete floors and ceilings in which hollow spaces between the walls, girders or beams, and between the floors and ceiling, are produced by space-forming boxes. Such boxes are also arranged to form between them spaces or forms for the casting in place of the concrete girders or beams, and remain a permanent part of the structure.

The invention has for its objects to strengthen, cheapen and improve such constructions in various particulars, and it consists in the parts and combinations thereof, and in the process of construction, herein-after set forth and claimed.

In order to make the invention more clearly understood, I have shown in the accompanying drawings means for carrying the same into practical effect, without limiting my improvements, in their useful applications, to the particular constructions which, for the purpose of explanation, I have delineated.

In said drawings:—Figure 1 is a sectional perspective view of a hollow concrete floor and ceiling constructed according to my invention. Fig. 2 is a vertical sectional view of the same. Fig. 3 is a side view of a sheet metal-plate, bendable and securable to form the side walls of a box. Fig. 4 is a perspective view of the top of the box, looking at the under side of the same. Fig. 5 is a perspective view of one of the sheets of reticulated metal. Fig. 6 is a vertical section illustrating a spacing means for the boxes. Fig. 7 is a similar view showing reticulated metal united to its box.

Referring to the drawings, 1 is a centering on which the ceiling and floor are cast. This centering is or may be a plane surface laid in the plane of the bottom surface of the ceiling to be constructed or in any equivalent manner, and suitably supported as by joists and posts 2, 3, or from the walls of the building. On this centering is laid a reticulated metal 4 of open mesh, to form a reinforcement for the ceiling panels beneath the hollow parts of the floor. Expanded metal of an inch and a half mesh

is suitable for this purpose. Or woven wire fabric or rods or wires properly spaced apart are suitable for the purpose. By "reticulated metal" I mean any form or arrangement of metal which leaves spaces for the percolation of the cementitious material which is to form the ceiling, and by "open mesh" I mean that the openings between the rods, wires or strands are sufficiently large for this purpose. The metal 4 can be laid directly on the centering, or it may be blocked up a little, about one-quarter of an inch above the centering 1, by small dovetail-shaped blocks 20 of cement in a known manner. In certain combinations and procedures embodying my invention the entire surface of the centering may be covered continuously by one or more sheets of such metal but in other combinations and for other purposes I prefer to make and lay the metal 4 in independent sheets. Such independent sheets, may be one sheet for each space-forming box, as illustrated, or one sheet may extend under two or more boxes. By making the sheets of metal independent I save a considerable amount thereof which would otherwise extend under the beams, and the relatively small sheets are convenient to handle and lay, according to the requirements of the floor, without having to pay attention to the lapping of sheets and having such laps properly located. I also prefer to have metal connections extend from edges of the metal 4 upward at the outside of the boxes into the bodies of the concrete beams which are formed between the boxes, so as to be anchored in such beams. Such metal connections are preferably formed by bending up edges 5 of the independent sheets 4, as shown in Fig. 5.

On the metal 4, whether it be continuous or in independent sheets, I place space-forming boxes 6. By "boxes" I intend any devices adapted to produce hollow spaces between the floor and ceiling. Ordinarily they are of box-like form, as illustrated, but they may be of inverted U-shape consisting of two opposite walls and a top, and may be arranged with their open ends together so as to form a tunnel-like space of the desired length. In the construction illustrated the boxes 6 have four vertical walls and are arranged about six inches apart, thus providing for two-way concrete beams 7 formed in the spaces between the boxes. In the

spaces which run cross-wise of the span covered by the floor may be laid main beam reinforcing bars 8 of any suitable character, and the cross beams running at right angles to the main beams may be more lightly reinforced by rods 9.

It will be understood that my invention is not limited to the reinforcement of the beams, or to the character of such reinforcement. In short spans such reinforcement might be omitted. On the other hand my improved floor and ceiling may be carried by I-beams incased in cementitious material, such a beam being indicated at 10.

15 The space-forming devices or boxes 6 are preferably made with separate tops 11, so that cementitious material may be laid within the boxes after they are in place on the centering with the metal 4 beneath them; 20 also for the purpose of making and shipping the boxes and tops 11 in knock-down form. For the latter purpose the sides of the boxes are first made of a continuous plate of sheet metal, as indicated in Fig. 3.

25 In order to enable this plate to be readily and accurately bent into square form it is perforated at 12 along lines which are to become the corners of the box. Provision is made for uniting the ends of the plate at the 30 fourth corner, as by forming the plate with tongues 13 which may be bent around upon the contiguous sides of the box. At the lines on which the said tongues are to be bent the plate may be perforated as shown 35 at 14. I also prefer to give a beveled, tapering or dome shape to the upper part of the box 6, for the purposes of enabling the side walls to center and retain in place the top 11 and to form a concrete fillet 15 at the 40 juncture of the concrete beam 7 and floor 16. This is effected, in that form of the invention which is illustrated, by forming on the side walls of the box, along their top edges, flanges 17 which incline inward at an angle 45 of about forty-five degrees; and the top 11 is formed with corresponding flanges 18, which rest on the flanges 17 when the top has been applied to the box. The plates forming the sides of the boxes (Fig. 3), the tops, 50 (Fig. 4) and the reticulated metal sheets (Fig. 5) are all so shaped that they will nest for economical crating or bundling and shipment. They may be shaped by any suitable dies and press.

55 The parts being shaped and constructed as above described, or in such equivalent manner as may embody the invention, and the boxes 6, without their tops, having been placed on the said metal 4, I fill into the 60 boxes sufficient fluid or semi-fluid cement grout 19 to form ceiling panels of substantially the shape and area of the boxes. The grout may be composed of sand, cement and water in suitable known proportions to cause 65 the same to set and become hard. The grout

may be more or less coarse, provided it will pass through the interstices of the metal 4 and envelop the strands or parts of the same. This body of grout may be of more or less thickness, say from one-half inch upward. It is relatively thin, the ceiling panels being independent of the floor and required only to support their own weight, and their extreme thinness relieves the floor as a whole of much weight which has been inevitable in other known structures. At the same time the metal reinforcement 4 does or may contribute to the support of the whole structure. Around the sides, under the edges of the boxes, the grout will flow out more or less into the beam spaces, and unites the ceiling panels integrally with the concrete beams when they are filled in, so as to form a monolith of all the cementitious material. The tops 11 are then applied to the boxes, as seen in Fig. 1. The reinforcing bars 8 and 9, if they are employed, may then be placed and supported in any known manner an inch and a half or two inches above the centering. This arrangement brings the beam reinforcements above the top level of the ceiling slabs, thereby resulting in a very thin and light ceiling slab, but one which is sufficiently strong and is well secured. The wet concrete is then filled in between the boxes to unite with the grout at the edges of the boxes, to embody the metal connections 5, to embody the reinforcements 8 and 9 and to form beams 7; and such filling is continued over the boxes to a proper thickness to form a concrete floor 16 integral with the beams. After the cementitious material, including the grout and concrete, has set, the centering is removed, leaving the boxes in place as permanent parts of the structure. Grout may be used for the lower parts of the beams if desired, up to the tops of the metal connections 5, or other preferred height. The fillets 15, of concrete integral with the beams and floor, strengthen the 105 structure materially, increasing the effective area of the beams and reducing, in effect, the span of the floor panels. The centering may be marked off, as by chalk, for the location of the boxes, or of the independent sheets of metal 4, and these movable parts may be lightly tacked or secured temporarily to the centering. Or the boxes may be held spaced properly apart by connections extending from one box to another and engaging the same. In Fig. 6, 21 is a metal connection formed with notches 22. This connection passes through slots 23 in the sides of any two contiguous boxes and engages the sides of the same by the notches 22. Each box may have one or more of the connections 21 at each of its sides. These connections may also be used to support the reinforcing bars, as shown in said figure, and furthermore may be formed with seats 24 for such bars. 110

The boxes 6 may be secured, as by wires 25, to the metal 4 beneath them, as shown in Fig. 7, and in such case the edges of the sheets of such metal may not be bent upward, though it is preferred that they be so bent.

The operation or process of constructing the described floor and ceiling is simple, convenient and economical; it may be conducted, 10 with the least labor and with great despatch; and the metal parts which enter into the structure are relatively inexpensive, especially when the effect produced is considered. The metal forms or boxes and sheets 15 of metal open work may be factory-made by a simple operation, and can be transported nested in small bulk without risk of deformation. The least weight of material and of the whole structure for the result attained is required. The ceiling does not need 20 to be plastered, this expensive operation being done away with, and any light finishing coat being sufficient. By the use of the invention a considerable economy results in 25 the building of such structures.

After the centering has been erected, which in itself is a simple and convenient affair involving the minimum of lumber and labor, the metal 4 and the boxes may be first 30 laid along one side or end of the floor space, and the grout filled into the boxes, the tops or covers 11 applied to the boxes, and the beam reinforcements put in place. This is the preferred way of performing my process. 35 While this is being done the rest of the centering is free to be walked on by the workmen while they are engaged in the operation. Then more open mesh metal sheets and the boxes are placed until a sufficient part of the 40 floor is ready for the concrete to be filled in. During much of the time the workmen can walk and stand in the spaces between the boxes, which would not be practicable if the whole surface of the centering were first 45 covered with the thin body of fluid cementitious material, because the thin and fluid ceiling panels would be impaired by the feet and wheelbarrows of the workmen. For the final beam and floor-laying operation, as a 50 convenience in filling in the concrete therefor, boards may be laid on the tops of the boxes on which the workmen may stand and walk. And such boards may also be used at any 55 stage of the process, as may be practical and desirable. At or near the bottom edges of the boxes I may provide openings 28 through which grout may flow from within the boxes into the beam spaces, or through which concrete may flow from the beam spaces to the 60 grout within the boxes, to unite integrally with the same to form a monolithic structure of the cementitious material.

In some forms of the invention the space-forming devices or boxes are not made of sheet metal, though the latter is usually pre-

ferred, but of other material such as cement reinforced or otherwise. The spacing and arrangement of the boxes or forms may be other than that illustrated. When inverted U-shaped open-ended boxes or forms are 70 employed, as hereinbefore mentioned, the fluid cement grout may be applied before or as the forms are placed.

The giving of a firm and unyielding bottom support to the space-forming devices 75 that they may be held from sinking down during the filling in of the beams and floor and thereafter, before the cementitious material has set, is of material importance. I obtain such a support from the centering 80 through the medium of the metal 4, on which latter, notwithstanding its embodiment in the grout, the space-forming devices rest, in the preferred form of my invention.

Horizontal and vertical stiffening ribs or 85 corrugations of suitable arrangement may be formed in the sides and tops of the boxes 6. These corrugations, certain of which are shown at 26, are by preference formed in the operation of pressing or forming the 90 tops and the blanks (Fig. 3) for the sides, by stretching the sheet metal without reducing the area of the blanks. Such ribs or corrugations also aid in interlocking the boxes with the concrete.

27 indicates metal connections, such as 95 wires, which may be used to join the metal 4 with the spacing bars or connections 21 that regulate the distance apart of the boxes 6. These connections 27 may be employed together with or in place of the 100 wires 25.

What I claim is:—

1. The herein described process of constructing hollow concrete floors and ceilings; 105 which consists in laying a continuous centering in the plane of the bottom surface of the ceiling; laying directly on the said centering metal of open mesh; providing therefor anchorage within the concrete of the 110 beams; placing a relatively thin layer of fluid cement grout and space-forming boxes on the said metal whereby the grout barely embodies the metal and the boxes rest on the 115 said metal; arranging metal reinforcement in the beam spaces above the top level of the ceiling; and before the said grout sets, filling concrete into the spaces between the boxes to form supporting beams integral with the said grout and over the boxes to 120 form a floor, substantially as set forth.

2. The herein described process of constructing hollow concrete floors and ceilings; 125 which consists in laying a continuous centering in the plane of the bottom surface of the ceiling; laying directly on the said centering metal of open mesh; providing therefor anchorage within the concrete of the beams; arranging space-forming boxes on the said metal so as to form beam spaces 130

between the boxes; filling on to the centering within the boxes a thin layer of fluid cement grout so as to form a ceiling embodying the said metal; then applying tops 5 over the boxes; arranging metal reinforcements in the beam spaces and before the said grout sets, filling concrete into the spaces between the boxes to form supporting beams integral with the said grout and over the 10 boxes to form a floor, substantially as set forth.

3. In a hollow concrete floor and ceiling, in combination: a concrete floor; beams comprising metal reinforcements and concrete 15 cast integral with the floor; and thin cast ceiling slabs integral with the concrete of the said beams, arranged to leave spaces below the floor, and having their top surfaces below the level of the said reinforcements; 20 and ceiling slab reinforcements in the lower parts of said slabs and barely covered by the same and having means whereby said ceiling slabs are anchored in the concrete of the beams; substantially as specified.
- 25 4. In a hollow concrete floor and ceiling, a series of space-forming boxes arranged between the floor and ceiling, a plurality of

independent sheets of metal of open mesh arranged under the said boxes, edges of which sheets are extended upward outside of 30 the boxes into the concrete of the beams between the boxes, and a body of cementitious material lying below the boxes and in the interstices of the said metal and barely covering the same to form a thin ceiling and between the boxes to form supporting beams, 35 and above the boxes to form a floor, substantially as set forth.

5. A reinforcement for hollow concrete floors and ceilings, consisting of hollow 40 boxes having bottoms of open work metal, the open work edges of which bottoms are extended upward and outward at the sides of the boxes for embedding in and interlocking with the concrete of the beams when the latter are formed in the spaces between the 45 boxes, substantially as specified.

In testimony whereof I affix my signature in presence of two witnesses.

JOHN F. GOLDING.
